(57) CLAIM

The ornamental design for a canvas greeting card, as shown and described.

DESCRIPTION

FIG. 1 is a perspective view of the canvas greeting card in unfolded state showing my new design.

FIG. 2 is a front view thereof.

FIG. 3 is a back view thereof.

FIG. 4 is a perspective view, wherein the canvas greeting card is in a folded state.

FIG. 5 is an enlarged view of the portion taken from the surface of the canvas greeting card depicted in the detail circle of FIG. 1; and,

FIG. 6 is an enlarged view of the portion taken from the surface of the canvas greeting card depicted in the detail circle of FIG. 1.

The broken line showing the words "text or design" is included for the purpose of illustrating environmental structure and forms no part of the claimed design.
